UNITED STATES PATENT OFFICE.

STEPHAN PICHLER, OF BROOKLYN, NEW YORK.

SCAFFOLD.

1,073,925.

Specification of Letters Patent. Patented Sept. 23, 1913.

Application filed October 17, 1912. Serial No. 726,192.

To all whom it may concern:

Be it known that I, STEPHAN PICHLER, a citizen of the United States, residing at Brooklyn, county of Kings, and State of New York, have invented a new and Improved Scaffold, of which the following is a specification.

This invention relates to a scaffold of novel construction, which may be quickly set up, is readily adjustable and separable, and possesses superior strength and rigidity.

In the accompanying drawing: Figure 1 is a side view of a scaffold embodying my invention; Fig. 2 an end view thereof; Fig. 3 an end view of one of the scaffold sections; Fig. 4 a side view of parts of the two scaffold sections showing them placed side by side; Fig. 5 a detail of part of the scaffold showing the base frame raised; Fig. 6 a perspective view of the connection between base frame and upright; Fig. 7 an enlarged section on line 7—7, Fig. 1; Fig. 8 a section on line 8—8, Fig. 7; Fig. 9 a detail of the brace-couplings; Fig. 10 a detail of the platform support; Fig. 11 a perspective view of a running board bracket, and Fig. 12 a top view thereof with one of the posts in section.

The scaffold comprises two or more units of substantially equal construction which may be raised one above another or be entirely separated. Each unit or section is provided with a base composed of a pair of longitudinal beams 13 resting with their ends upon the ends of a pair of cross beams 14, which are supported on casters 14^a. Beams 13 are connected to beams 14 by belts 15, so as to constitute an open frame. At each end, beams 13 are apertured above beams 14 as at 16 for the reception of a yoke 17, into which the lower end of an upright corner post 18 is removably fitted so as to rest upon beam 14. Sidewise of apertures 16, beams 13 are provided with an additional perforation 19, which is clear of beam 14 and is so spaced that the yoke may also be inserted with its shanks into this perforation and the adjoining perforation 16. Thus by manipulating the yoke-holding nuts 20 and shifting the yoke sidewise, the post 18 may be set to clear beam 14 and in this way the base frame may be slid upward along the posts, which will form guides at the corners of the frame. The frame thus raised may be held at any suitable elevation above the floor by tightening up nuts 20,

so that in this way the device is supported solely upon the ends of the corner posts. This adjustment is resorted to when the scaffold is to clear benches 21 or other floor-fixtures (Fig. 5). The adjoining posts 18 of the upper and lower scaffold sections are adapted to be connected by bolts 22 engaging corresponding perforations 23, a row of such perforations being formed in each post, so that in this way the upper section may be supported by the lower section at a suitable elevation above the floor. The uppermost perforations 23 of posts 18 are engaged by bolts 24 upon which are hinged 70 eyed bails 25. These bails pass through corresponding apertures of transverse joists 26 upon which are placed the planks 27 of the platforms.

To the two upper corners of the upper scaffold section, constructed as described, are pivoted by bolts 28, a pair of diagonal end braces 29, while to the center of beam 14 of the lower scaffold section, is pivoted at 30, a pair of corresponding braces 31. 80 Each brace 29 is aligned with its companion brace 31 which it overlaps and to which it is removably connected by couplings or slides 32 carrying tightening screws 33. Thus when the two platform sections are superposed, the braces will form a unit extending from the bottom to the top of the compound structure (Fig. 2). If however the two scaffold sections are to be separated from each other to form two smaller distinct devices, slides 32 are manipulated to uncouple braces 29 from braces 31. The upper braces 29 are then swung inward at their lower ends and connected to a common pivot 34 at the center of the upper beam 14, while 95 the lower braces 31 are swung outward at their upper ends and bolted to the lower posts 18 at the corresponding apertures 23 (Fig. 3). In this way each segregated scaffold section is properly braced at its 100 ends from top to bottom. In addition to the end braces, constructed as described, the device is provided with side braces made in all respects similar to the end braces. Thus there are pivoted to the upper corners of 105 the upper scaffold section at 35, the side braces 36. These braces are removably connected by slides 37 to the overlapping ends of braces 38 pivoted at 39 to the center of the longitudinal beam 13 of the lower scaffold section. If the two sections are to be 110 separately used, the lower ends of the up-

per braces 36 are connected to a common pivot 40 at the center of upper beam 13, while the upper ends of the lower braces 38 are pivoted at 41 to the upper ends of the 5 lower uprights 18.

As shown in Fig. 4, the two scaffold units, when separated from each other, may be placed side by side and so spaced as to accommodate between them, a platform 42 bolted to uprights 18 at any of the apertures 23. In this way, the length of the structure may be increased to any extent desired, so that an extensive wall surface is accessible to the operator.

15 Means are provided for adjustably securing running boards to both sides of the scaffold. These means comprise apertured brackets 43, to which are bolted at 44, flanged plates 45 that straddle posts 18 and are 20 adapted to be removably connected thereto by bolts 46 engaging either of the perforations 23. Upon each pair of brackets 43, a running board 47 is placed, so as to project from the side of the structure and thus increase its working surface.

I claim:

1. A scaffold comprising a plurality of corner uprights, platform-sustaining means

carried thereby, a base frame composed of a pair of longitudinal beams and a pair of 30 cross beams that are secured to the ends of the longitudinal beams, said frame being adapted to encompass the uprights and to be slidably along the same, and means for detachably securing the frame to the uprights at an elevation above the lower ends thereof.

2. A scaffold unit comprising a base-frame, a plurality of yokes carried thereby, means for setting said yokes either vertically above or sidewise of part of said frame, a plurality of uprights encompassed by said yokes, and platform-sustaining means carried by said uprights.

3. A scaffold unit comprising a base-frame, composed of longitudinal and transverse beams, one set of said beams having yoke receiving means above and also sidewise of the other set of beams, yokes adapted to engage either of said means, uprights 45 encompassed by said yokes, and platform-sustaining means carried by said uprights.

STEPHAN PICHLER.
